ABSTRACT

An electric ground connector plug using three parallel bare rigid conductors snap fitted into a front opening of a hollow elongated non-conductive body by means of a removable non-conductive insert. The rigid conductors have rear ends disposed in the body and bent to conform with chamfered peripheral surfaces disposed about a rear opening in the body. One end of a cable is disposed in the rear opening. The cable contains three insulatedly separated flexible conductors, each flexible conductor being secured by a screw to a corresponding rigid conductor adjacent the rear opening in the body.

FIG. 2

FIG. 1

FIG. 4

FIG. 5

FIG. 3

ELECTRIC GROUND CONNECTOR PLUG

SUMMARY OF THE INVENTION

This invention is directed toward a safe inexpensive easily manufactured electric ground connector plug for use with appliances and the like.

To this end, an elongated hollow non-conductive body has a cable receiving rear opening and an enlarged front opening. A removable non-conductive insert slidably fits in the front opening of the body. The abutting peripheral surfaces of insert and body define three spaced bores. Each bore is adapted to receive an elongated bare conductor.

Three parallel bare rigid conductors extend in the same direction as the direction of elongation. Each rigid conductor is disposed in friction tight engagement with the corresponding bore and extends therethrough with front ends exposed and rear ends disposed in the interior of the body. Each rear end has a transverse threaded opening engaged by a corresponding removable screw.

In use, one end of a cable is disposed in the rear opening of the body. The cable contains three flexible conductors insulatedly separated from each other. One end of each flexible conductor is detachably secured between a corresponding screw and the bare conductor receiving the corresponding screw.

Additional strength and rigidity can be obtained by chamfering the peripheral surfaces within the body disposed about the rear opening and bending the rear ends of the rigid conductors so that these rear ends conform to these surfaces. The bare conductors are thus effectively locked in position and will not shift when the plug is inserted into a female socket or removed therefrom.

BRIEF DESCRIPTION OF THE DRAWINGS

In the drawings:

FIG. 1 is an exploded view of one form of the invention;

FIG. 2 is an assembled front end view of the structure of FIG. 1;

FIG. 3 is a cross section of a modification of FIG. 1;

FIG. 4 is a cross sectional view of another modification of the invention; and

FIG. 5 is a detail view of a portion of the structure shown in FIG. 4.

DETAILED DESCRIPTION OF PREFERRED EMBODIMENTS

Referring first to FIGS. 1 - 2, an elongated hollow electrically non-conductive body 10 has an enlarged front opening 12 and a cable receiving rear opening 14. A removable electrically non-conductive insert 16 slidably fits into the front opening leaving a hollow chamber 18 in the body. The mating peripheral surfaces of insert and body define three spaced longitudinal bores 20. The chamfered peripheral surfaces 22 disposed in the chamber around opening 14 are adapted to receive conforming bent rear ends 30, 32 and 34 of rigid bare conductors 24, 26 and 28.

The conductors 24, 26 and 28 disposed in parallel

position extend longitudinally through the bores with front ends exposed and rear ends disposed as described. The conductors are thus locked in place.

Each bare conductor has a transverse threaded hole 36 adjacent its rear end and removably engaged by a corresponding screw 38.

In use, one end of cable 40 carrying three flexible conductors 42 insulatedly separated from each other is disposed in opening 14, each conductor being removably held between screw and bare conductor to make appropriate electrical connections.

Conductors 24 and 26 are flat and oppositely disposed. Ground conductor 28 is U shaped in cross section.

As shown in FIGS. 4 and 5, conductors 24 and 26 can have transverse slots 44 disposed adjacent ends 30, 32 and 34 to accomodate portions of conductors 42 adjacent the screws to provide additional structural support against breakage of connections.

As shown in FIG. 3, the holes 36 can be disposed in the bent ends and the screws 38 disposed in place to hold conductors 42 in suitable position.

While the invention has been described with detailed reference to the drawings, the protection sought is to be limited only by the terms of the claim which follows.

We claim:

1. In combination with an electric cable having three flexible conductors insulatedly separated from each other, an electric ground connector plug comprising: an elongated hollow non-conductive body having a cable receiving rear opening in which one end of the cable is disposed, the end of the rear opening within the body having a chamfered periphery, said body having an enlarged front opening; a removable non-conductive insert slidably fitting in the front opening, the abutting peripheral surfaces of the insert and the body defining three spaced bores, each bore being adapted to receive an elongated bare conductor; three screws; and

three parallel bare rigid conductors extending in the same direction as the direction of elongation, each conductor being disposed in friction tight engagement with the corresponding bore and extending therethrough with front ends exposed and rear ends disposed in the interior of the body, each rear end of each bare conductor being bent to conform with the appropriate portion of the chamfered periphery to impart additional rigidity to the structure and having a transverse threaded hole threadedly engaged by the corresponding screw, one end of each flexible conductor being detachably secured between a corresponding screw and the bare conductor receiving the corresponding screw, one selected rigid conductor being used for the ground conductor and having U-shaped cross section, the remaining two rigid conductors each having a transverse slot adjacent the corresponding screw for accomodating a portion of the corresponding flexible conductor.
